UNITED STATES PATENT OFFICE

139,729

DESIGN FOR AN AIRPLANE

Alexander Kartveli, Huntington Station, and Murray Berkow, Flushing Heights, N. Y., assignors to Republic Aviation Corporation, a corporation of Delaware

Application January 18, 1944, Serial No. 112,259

Term of patent 14 years

(Cl. D71—1)

To all whom it may concern:

Be it known that we, Alexander Kartveli and Murray Berkow, citizens of the United States, and respectively residents of Huntington Station, Long Island, New York, and Flushing Heights, New York city, New York, have invented a certain new, original, and ornamental Design for an Airplane of which the following is a specification, reference being had to the accompanying drawings, forming part thereof.

In the drawings,

Fig. 1 is a top plan view of an airplane embodying the present design with the landing gear protracted;

Fig. 2 is a side elevation thereof with the landing gear protracted;

Fig. 3 is a front view thereof with the landing gear retracted; and

Fig. 4 is a rear elevation thereof with the landing gear retracted.

What is claimed is:

The ornamental design for an airplane, substantially as shown.

ALEXANDER KARTVELI.
MURRAY BERKOW.
